Specification for Design.

Patented June 23, 1914.

Application filed April 14, 1914. Serial No. 831,834. Term of patent 14 years.

To all whom it may concern:

Be it known that I, OSWALD M. Gross, a citizen of the United States, residing at Chicago, in the county of Cook and State of Illinois, have invented and produced a new, original and ornamental Design for a Vehicle-Body, of which the following is a specification, reference being had to the accompanying drawing, forming a part thereof.

Figure 1 is a view of the improved vehicle

body in side elevation. Fig. 2 is a view of the body in front elevation. Fig. 3 is a view of the body in rear elevation. Fig. 4 is a perspective view of the body.

I claim—

The ornamental design for a vehicle body as shown.

OSWALD M. GROSS.
